Des. 217,983
Patented July 7, 1970

217,983

PROCESS CONTROL INSTRUMENT

Robert F. Wall, Chesterfield, Mo., assignor to Monsanto
Company, St. Louis, Mo., a corporation of Delaware
Continuation-in-part of design application Ser. No.

12,629, July 5, 1968. This application Sept. 9,
1969, Ser. No. 19,076

Term of patent 14 years

Int. Cl. D10—10

U.S. Cl. D52—6

FIG. 2

FIG. 5

FIG. 6

FIG. 7

FIG. 3

FIG. 4

FIG. 1 is a front, perspective view of a process control instrument showing my new design;

FIG. 2 is a front view of the instrument of FIG. 1;

FIG. 3 is a left side view fragmentarily broken away for ease of illustration;

FIG. 4 is a right side view of the instrument of FIG. 1;

FIG. 5 is a top plan view of the instrument of FIG. 1;

FIG. 6 is a bottom plan view of the instrument of FIG. 1; and

FIG. 7 is a rear view of the instrument of FIG. 1.

This application is a continuation-in-part of my application Ser. No. D-12,629, filed July 5, 1968, now abandoned.

The broken lines are shown for illustrative purposes only and do not form part of the claim.

I claim:

The ornamental design for a process control instrument, as shown and described.
